CLAIM

The ornamental design for a bottle for cosmetics as shown and described.

DESCRIPTION

FIG. 1 is a perspective view of a bottle for cosmetics showing my new design;

FIG. 2 is a front view thereof, a rear view thereof being identical to the front view;

FIG. 3 is a right side view thereof, a left side view thereof being identical to the right side view;

FIG. 4 is a top plan view thereof;

FIG. 5 is a bottom plan view thereof;

FIG. 6 is a cross-sectional view thereof taken along line 6-6 in FIG. 3; and,

FIG. 7 is a cross-sectional view thereof taken along line 7-7 in FIG. 3.

The broken lines depict portions of the bottle for cosmetics that form no part of claimed design.

1 Claim, 7 Drawing Sheets
